UNITED STATES PATENT OFFICE.

BERNARD TAUMAN, OF CHICAGO, ILLINOIS.

DESIGN FOR A FISH-BOWL SUPPORT.

Application filed July 9, 1928. Serial No. 27,418. Term of patent 3½ years.

To all whom it may concern:

Be it known that I, BERNARD TAUMAN, a citizen of the United States, and resident of Chicago, in the county of Cook and State of Illinois, have invented a new, original, and ornamental Design for Fish-Bowl Support, of which the following is a specification, reference being had to the accompanying drawing, forming part thereof, in which

Fig. 1 is a front elevation of the article, showing my new design; and

Fig. 2 is a side elevation of same.

I claim:

The ornamental design for a fish bowl support, as shown.

BERNARD TAUMAN.
